UNITED STATES PATENT OFFICE

ERNEST A. KING, OF PHILADELPHIA, PENNSYLVANIA, ASSIGNOR TO HENRY DISSTON & SONS, INCORPORATED, OF PHILADELPHIA, PENNSYLVANIA, A CORPORATION OF PENNSYLVANIA.

PLUMB.

1,246,609.

Specification of Letters Patent.

Patented Nov. 13, 1917.

Application filed May 2, 1917. Serial No. 165,926.

To all whom it may concern:

Be it known that I, ERNEST A. KING, a citizen of the United States, residing in Philadelphia, Pennsylvania, have invented 5 certain Improvements in Plumbs, of which the following is a specification.

My invention relates to certain improvements in plumbs used in connection with a level and is a companion application to one 10 filed even date herewith relating to improvements in levels, Ser. No. 165,927.

One object of my present invention is to provide means for adjusting the frame carrying the glass tube in which the bubble is 15 located.

A further object of the invention is to make a double plumb, one frame carrying one tube and another frame carrying the other tube.

20 In the accompanying drawings:

Figure 1 is a side view of my improved plumb;

Fig. 2 is an edge view of the plumb, partly in section;

25 Fig. 3 is a sectional view of a portion of the plumb illustrating the two frames; and

Fig. 4 is a detached perspective view of one of the frames.

Referring to the drawings, 1 is the body 30 portion having an opening 2, closed by glazed frames 3 at each side. Pivotedly mounted in the opening 2 are segmental frames 4 and 5 pivoted respectively at 6 and 7, the two frames resting on a shoulder formed on the body portion, as clearly shown in Fig. 2. Each of the two glazed frames is constructed of two members having a glass disk between them. One of the members has a flange adapted to be secured 35 to the body of the plumb.

Carried by the segmental frame 4 is a tube 8 and carried by the segmental frame 5 is a tube 9, each having a bubble therein. These two frames can be independently adjusted 45 so that the bubble can be properly centered. The adjusting means in the present instance consists of a screw 10 having a head 11. The screw extends into a

threaded opening in one of the forks of each frame 4 and 5, as clearly shown in Fig. 3, 50 and the head of the screw, which is rounded in the present instance, is clamped between a washer 12 and a clamp plate 13 in a recess 14 in the edge of the body of the plumb. Screws 15 are used to clamp the plate 13 55 firmly on the head of the screw 10 and thus hold it in the position to which it is adjusted. The head 11 of the screw extends through an opening in the plate, the walls 60 of which are beveled or curved to conform to the head of the screw. By this means the screw can be turned to adjust the frames carrying the tubes without dismantling the parts. All that is necessary is to move the cap plate 16, which covers the adjusting 65 means, and is flush with the edge of the body portion.

It will be noticed that the fork on one side of each of the frames 4 and 5 is longer than the other. This allows for the forming of 70 a threaded opening in the fork to receive the adjusting screw.

From the above description, it will be seen that I make a very simple form of plumb of the type using a glass in which 75 there is a bubble. The plumb can be adjusted without dismantling the parts and the bubble can be seen from every side through the glazed frames.

By making the plumb with the frames, 80 as shown, it can be used either end up so that it is very convenient, particularly where a long line is to be plumbed.

I claim:

1. The combination in a plumb, of a body 85 portion having a circular opening therein recessed at each side; two opposed, segmental frames arranged in said opening and in the same plane and having projections adapted to the recesses; pivots extending 90 through the projections into the frame; a tube in each frame in which a bubble is located; and independent means for laterally adjusting each frame on its pivot.

2. The combination of a body portion 95 having an opening therein; two segmental

frames; a pivot for each frame; the two frames being so located in the opening in the body portion as to form a cylindrical opening; a glass tube mounted in each frame 5 and extending across the opening formed by the frames; an adjusting screw for each frame, one screw extending to one edge of

the plumb and the other screw extending to the opposite edge; and means for holding each screw in the position to which it is 10 adjusted.

In witness whereof I affix my signature.

ERNEST A. KING.
